UNITED STATES PATENT OFFICE.

CHARLES T. BOYER, OF INDIANAPOLIS, INDIANA, ASSIGNOR TO THE AMERICAN BUNCHER MANUFACTURING COMPANY, OF SAME PLACE.

BUNCHING ATTACHMENT FOR MOWING-MACHINES.

SPECIFICATION forming part of Letters Patent No. 558,149, dated April 14, 1896.

Application filed May 9, 1895. Serial No. 548,760. (No model.)

To all whom it may concern:

Be it known that I, CHARLES T. BOYER, a citizen of the United States, residing at Indianapolis, in the county of Marion and State of Indiana, have invented certain new and useful Improvements in Bunching Attachments for Mowing-Machines, of which the following is a specification.

The object of my said invention is to provide a convenient and efficient means whereby hay, in being cut, can be deposited in bunches directly from the mowing-machine instead of being distributed entirely over the surface of the field, as has been common with ordinary mowers. This is especially useful in cutting clover where it is desired to save the seed, it being desirable, as is well known, to leave such clover in bunches and subject to the action of the weather for a time, during which period it should be disturbed as little as possible.

Said invention consists in an attachment whereby the above object is carried out, as will be hereinafter more particularly described and claimed.

Referring to the accompanying drawings, which are made a part hereof, and on which similar letters of reference indicate similar parts, Figure 1 is a perspective view illustrating a mowing-machine in use, which is provided with an attachment embodying my said invention; Fig. 2, a top or plan view of said attachment, together with the cutting apparatus and other immediately-adjacent portions of the mowing-machine; Fig. 3, a perspective view of a fragment of said attachment on a larger scale, illustrating the principal parts, the upper plate or cover of the frame of said attachment being removed, exposing the mechanism; Fig. 4, a longitudinal sectional view on the dotted line 4-4 in Fig. 2, and Fig. 5 a transverse sectional view on the dotted line 5-5 in Fig. 2.

In said drawings the portions marked A represent the framework of the mowing-machine, B the finger-bar thereto, and C the frame of my improved attachment.

The mowing-machine A and finger-bar B are or may be of any ordinary or desired form, and will not, therefore, be further described herein, except incidentally in describing my said invention.

The frame C is hinged to the finger-bar B by hinges c, and is positioned directly in rear thereof. Mounted in bearings therein 55 are a number of rods C', which extend to the rear, the direction being preferably on somewhat of an inclination toward the mowing-machine and away from the standing grass, so that in manipulation, as will be presently 60 more fully explained, the grass which has been cut shall be thrown away from rather than against the standing grass. At the rear end these rods are bent upwardly, as shown most plainly at c' in Fig. 5, so that in their 65 normal position they will hold the grass from being pulled off by contact with the ground or stubble until the position is shifted and the bunch of cut grass thus purposely released. They are also preferably curved somewhat 70 from the point of bearing in the frame C to the point where they are bent upwardly, as just stated, so that, as indicated by the dotted lines in Fig. 2, when the upwardly-projecting ends are thrown down the body is thrown back 75 slightly, thus aiding in throwing the bunch of cut grass away from the standing grass. At their forward ends these rods have cranks, as shown most plainly in Figs. 3 and 5, and these are all connected to a sliding bar C², by which, 80 as will be readily understood, all said rods may be simultaneously operated. The longitudinal movement of this bar C² may be effected in any desired manner and is generally effected by means of a treadle, as A', operated by the driver. The connection may be in any form desired. I have shown a cord C³ running over suitable sheaves to said treadle A', the latter being mounted on the frame A at a suitable point for the driver to place his 90 foot thereon, as best shown in Fig. 2. A spring C⁴ is shown as interposed between shoulders on the bar C² and the inner surface of the frame C, and said spring is of sufficient strength to actuate said bar C² and tip the 95 rods C' connected thereto. The spring may of course operate in either direction, but I have shown it as operating to tip the rods flat, in the position shown by the dotted lines in Fig. 2, said rods being held to their other position by the force of the driver's foot on the treadle.

The top of the frame C is in the form of a plate C⁵, which extends back over and covers

the bearings of the rods C' and the mechanism by which they are operated, and is secured in place by hinges c⁵. This cover also serves to momentarily impede the grass as it falls during the time the bunches of grass are being discharged. Normally, while the bent-up points c' are raised to their greatest height, as shown most plainly in Fig. 5, the cranks on the other ends of the rods, which are connected to the bar C², are in their lowermost position. The forcing of said bar C² endwise not only rocks the rods C', but is, through the instrumentality of the cranks on the ends of said rods, also the means of raising the cover C⁵ to the position shown by the dotted lines in Figs. 4 and 5, and said cover in this position forms a dam or impediment, which will cause the grass as it falls to pile up for the brief period while the rods C' are rocked, so that their points c' lie flat. As the device is released and the points c' thrown up to their normal position the cover C⁵ falls flat again, as shown by the full lines in Fig. 5, and the grass passes on freely over it, as before, to against said bent-up points c', where a new bunch is formed.

The operation is as follows: The driver holds his foot on the treadle A', keeping the rods C' with their outer bent ends c' standing upright, as shown most plainly in Fig. 5, until a sufficient quantity of the grass has, in the operation of mowing, been thrown onto said rods to make the desired size of bunch. He then releases the pressure of his foot on said treadle, when said rods are thrown down to the position shown by the dotted lines in Fig. 2, when the friction on the ground and stubble draws the bunch off said rods and leaves it at the point where this operation is had. The rods are then thrown up to their former position by renewing the pressure on the treadle, and so on continuously as long as the machine is in operation or as long as it is desired to perform this work.

Having thus fully described my said invention, what I claim as new, and desire to secure by Letters Patent, is—

1. The combination, with a mowing-machine, of a bunching attachment secured be-

hind the finger-bar and consisting of a suitable frame with a series of rods journaled therein and provided with cranks on their forward ends and bent or divergent portions on their rear ends, and mechanism for operating said rods, whereby bunches of grass may be accumulated as said grass is cut, and then, by throwing the rods flat by means of said mechanism, discharged, substantially as set forth.

2. The combination, with a mowing-machine, of a bunching attachment consisting of a framework secured behind the finger-bar, a series of bent bars journaled in said framework and extending rearwardly and at an inclination toward the mowing-machine structure and having upwardly-turned rear ends, substantially as shown and described.

3. The combination, with a mowing-machine, of a bunching attachment secured in the rear of the finger-bar, and consisting of a framework, a series of rods journaled in said framework and provided with divergent ends at the rear and cranks at the forward ends thereof, a bar C² to which the cranks of said rods are all connected, a foot-lever mounted on the mowing-machine, a connection between said foot-lever and said bar, and a spring acting oppositely to the pull from said foot-lever, substantially as shown and described.

4. The combination of a mowing-machine; and a bunching attachment, secured in the rear of the finger-bar, and consisting of a frame C, rods C' mounted therein and provided with angular ends c', a bar C² connected to cranks on the forward ends of said rods whereby they are operated, and a plate C⁵ covering said operating mechanism, including said bar C², and adapted to be raised by said mechanism as the rods C' are rocked to deposit the bunch of grass thereon, substantially as shown and described.

In witness whereof I have hereunto set my hand and seal, at Indianapolis, Indiana, this 7th day of May, A. D. 1895.

CHAS. T. BOYER. [L. S.]
